UNITED STATES PATENT OFFICE.

JAMES E. SULLIVAN, OF PAWTUCKET, RHODE ISLAND.

ADJUSTING DEVICE FOR DRAFT-REGULATORS FOR STEAM-BOILERS.

1,143,737.

Specification of Letters Patent. Patented June 22, 1915.

Application filed July 20, 1914. Serial No. 852,093.

To all whom it may concern:

Be it known that I, JAMES E. SULLIVAN, a citizen of the United States, residing at Pawtucket, in the county of Providence and State of Rhode Island, have invented certain new and useful Improvements in Adjusting Devices for Draft-Regulators for Steam-Boilers, of which the following is a specification.

10 My invention relates to improvements in adjusting devices for draft regulators for steam boilers, and the purpose of my invention is to provide a method by which the extent of the opening and closing of dampers by means of the ordinary diaphragm arm may be quickly and accurately adjusted to meet changes in temperature. I accomplish this object by the device shown in the accompanying drawing, in which—

20 Figure 1 is an elevation of an ordinary heating boiler showing the damper-regulating diaphragm and lever with my adjusting device attached thereto. Fig. 2, an enlarged fragmentary elevation about one half the full size of my device. Fig. 3, a view of the same from above, showing a horizontal section of the pulley *b* of the device. Fig. 4, a vertical section through the line *x*—*x* of Fig. 2. Fig. 5, a detail of the pulley *b*, showing the friction spring *d*, and Fig. 6, a vertical section through the line *y*—*y* of Fig. 1.

The same parts are indicated by the same letters throughout the several views.

35 My device is intended and adapted to be attached to the lever of an ordinary diaphragm damper-regulator such as is used on most heating boilers. Consequently in Fig. 1 the only new matter disclosed is my device *a*, *b*, *c*, attached as shown to the outer or free lever of the damper-regulator, the other parts of the diaphragm regulator being the pivot *p*, and diaphragm piston *t*, and the weight *r*; *h* is the fire door and *h* a flap draft in the fire door, having the ordinary slides *h*² and the lifter attachment *h*². *l* at the lower part is an ash box damper having the attached lifter *l*’; *i* is a cord or chain attached to the lifter *l*’, thence running two or more turns over the pulley *b* of my adjusting device, thence over the ceiling

pulley *j*, and down to the lifter of the fire door flap *h*².

Prior to my invention, the only method, so far as I know, of adjusting the amount of opening of the dampers has been by using a chain and changing the length of the chain by means of a hook at the extremity thereof, hooking it into different links as occasion demanded; or, if a cord instead of a chain is used, by tying knots in the cord and letting them out again for different changes of temperature. It is readily seen that this is a crude, and at the best unsatisfactory method of adjusting the drafts for changes of weather, and the purpose of my device is to provide a means by which the degree or amount of opening of the various dampers may be quickly adjusted by means of a revolving pulley or drum, and by providing a graduated edge and a pointer so that after experiment, the dampers may be instantly set for any condition of atmosphere.

In Fig. 1, my device is seen attached to the outer or free end of the diaphragm lever *r*. Figs. 2, 3 and 5, however, disclose more completely the construction of my device. In these figures, *a* is a metallic arm or rod provided with the lugs *a*²—*a*², the bar *a* being adapted to be placed upon the flat side of the diaphragm lever *r*, and the lugs *a*²—*a*² being adapted to be bent over the upper edge of *r*, as shown best in Fig. 4, which is a sectional view on the line *x*—*x* of Fig. 2. In order to retain *a* in place upon the diaphragm lever an ordinary bolt or set-screw *a*³ is used. The outer extremity of the bar *a* carries upon it a revoluble drum *b* mounted upon a spindle *c*—*c*’ which goes through the bar *a* and is secured upon the back by the nuts *f*—*f*’, as shown best in Fig. 3. Between the bar *a* and the drum *b* is introduced the washer *e*. The drum *b* is grooved upon the periphery as shown at *b*’ in Fig. 3, and is provided with a small screw *b*² for the purpose of insuring the chain or cord *i* from sliding upon the drum. The bar *a* also carries a projecting member *a*⁴ which serves the double purpose of an index pointer and also to retain the cord or chain in place in the groove *b*’ of the drum *b*. The face of the drum *b* adjacent to the

washer e is recessed as shown in Figs. 3 and 5 and in this recess is placed a split friction-washer d secured to the face of the drum by the screw d' , Fig. 5. The free end 5 of the friction-washer d normally projects above the surface of the drum b and its tension is sufficient when the nuts $f-f'$ are screwed up to keep the drum b from revolving by the weight of the dampers, and yet 10 not too great to prevent the drum from being moved by the fingers.

The outer face of the drum b , Fig. 2, is graduated at that portion adjacent or near to the pointer a^4 , and may bear the letters 15 "m", "c", "z", standing respectively for "mild", "cold" and "zero", and indicating the point where the periphery of the drum should be placed to suit these respective conditions of atmosphere.

20 The operation of my device is as follows:—One free end of the cord i is attached to the lifter h^2 of the fire-door flap and passes thence over the pulley j in the ceiling k , then downward about the drum b , making 25 two or three turns thereof clockwise, a loop being made over the screw b^2 so as to insure the cord from slipping. The other free end of the cord i is then carried downward and fastened to the lower draft damper l , as 30 shown in Fig. 1. It will thus be seen that the drum b , the diaphragm lever r , and the cord i are practically integral, and as long as there is no revolution of the drum b , the cord i and the attached dampers move with 35 the diaphragm lever r as though the cord were fastened thereto directly. The relative positions of the lever r and the draft doors l and h are determined experimentally while the drum b is loose upon the bar a , 40 and having been thus determined the cord i is fixed in place upon the drum by the screw b^2 and the drum tightened by means of the spindle c and the nuts $f'-f$. We will now suppose that an approach of colder 45 weather requires the draft door l to be open wider or longer and a corresponding quicker closing of the fire-door flap h ; instead of shortening chains, or making knots in cords, all that is necessary is with the finger and 50 thumb to revolve the drum b until the pointer a^4 is nearer to or opposite the letter "z" on the periphery of the drum. This instantly changes the relative position of the diaphragm lever, the cord, and the flaps h and l , thus insuring the required result. 55 Upon the approach of milder weather, the drum is revolved until the pointer is opposite or near the letter "m" which will result in the flap h of the fire-door being kept 60 open for a longer period and the draft flap l closed sooner and kept closed longer.

The drum b is adapted to carry either the cord, the chain, or any other flexible connection, and any required degree of opening

or closing of the flaps h and l may be accomplished readily and quickly by means of the graduated marks upon the drum b .

It is evident that by an auxiliary branch of the cord or chain a pipe damper may be controlled in the same manner as the ash- 70 door and fire-door dampers.

In practice my device has greatly increased the ease of adjusting the damper movements and has made the operation of house boilers very much easier than by the 75 use of the ordinary methods of damper regulation.

Having now described my invention, what I claim and desire to secure by Letters Patent is—

80

1. An adjusting device for diaphragm-operated dampers of steam boilers, consisting of a disk adapted to be revolubly mounted upon the diaphragm lever of the boiler; a cord or other flexible body adapted to be 85 peripherally wrapped around said disk intermediate its ends, means for holding the cord in fixed relation to said disk, the free ends of said cord being attached to the draft dampers of said boiler; and means for retaining said disk in any predetermined position of revolution upon its axis.

90

2. An adjusting device for diaphragm-operated dampers of steam boilers, consisting of a clamping member capable of being 95 fixed upon the diaphragm lever; a graduated disk adapted to be revolubly mounted upon said clamping member, and having a circular lateral recess adjacent to its axis; a cord or other flexible body encircling said disk peripherally and adapted to be held in fixed relation thereto, the free ends of said cord being attached to the draft dampers of said boiler; a split lock-washer fitting said recess; and means for varying the pressure 100 between said disk and washer.

105

3. An adjusting device for diaphragm-operated dampers of steam boilers consisting of a clamping member suitably fixed upon the diaphragm lever; a disk having 110 graduated marks at the circumference thereof adapted to be revolubly mounted upon said clamping member and having a circular lateral recess adjacent to its axle; a cord or other flexible body encircling said disk peripherally and adapted to be held in fixed relation thereto, the free ends of said cord being attached to the draft dampers of said boiler; a split lock-washer fitting said recess, a bolt forming an axle for said disk 115 and supported by the diaphragm lever, or by said clamping member; and nuts operating to vary the pressure between said disk and washer.

120

4. An adjusting device for diaphragm-operated dampers of boilers comprising a 125 supporting member, a disk revolubly-mounted thereon, a flexible member connected at

its ends to said dampers, said flexible member being wound on said disk and secured intermediate its ends to said disk whereby when said disk is rotated the dampers will 5 be selectively positioned, and means for retaining said disk in adjusted positions.

In testimony whereof I affix my signature in presence of two witnesses.

JAMES E. SULLIVAN.
